US00D788078S

(12) **United States Design Patent** (10) **Patent No.:** **US D788,078 S**
Lee et al. (45) **Date of Patent:** **** May 30, 2017**

(54) **ANTENNA**

(71) Applicants: **AGC AUTOMOTIVE AMERICAS R&D, INC.**, Ypsilanti, MI (US); **AGC Flat Glass North America, Inc.**, Alpharetta, GA (US)

(72) Inventors: **Ming Lee**, Ypsilanti, MI (US); **Jesus Gedde**, Dexter, MI (US); **Frederick M. Schaible, III**, Grosse Pointe Park, MI (US); **Yasutaka Horiki**, Ypsilanti, MI (US); **Jun Noda**, Canton, MI (US)

(73) Assignees: **AGC AUTOMOTIVE AMERICAS R&D, INC.**, Ypsilanti, MI (US); **AGC FLAT GLASS NORTH AMERICA, INC.**, Alpharetta, GA (US)

(**) Term: **15 Years**

(21) Appl. No.: **29/546,486**

(22) Filed: **Nov. 23, 2015**

Related U.S. Application Data

(62) Division of application No. 29/480,024, filed on Jan. 22, 2014, now abandoned.

CLAIM

The ornamental design for an antenna, as substantially shown and described.

DESCRIPTION

FIG. 1 is a front plan view of an antenna according to the present invention;

FIG. 2 is a rear plan view thereof; and,

FIG. 3 is a front plan view of the antenna in use.

All surfaces of the claimed design are flat and coplanar. The broken lines in FIG. 3 illustrate environment and form no part of the claimed design.

1 Claim, 1 Drawing Sheet
